(57) **CLAIM**

The ornamental design for a multi-tiered container blank, as shown and described.

DESCRIPTION

The sole FIGURE is an overhead plan view of the multi-tiered container blank according to the present invention. The broken lines in the drawing depict parts of the multi-tiered container blank that form no part of the claimed design; while the dashed lines with the thin solid line through the center depict fold lines and form a part of the claimed design.
